UNITED STATES PATENT OFFICE

DOROTHY FLEETWOOD, OF FORT LAUDERDALE, FLORIDA

METHOD OF DECORATING

No Drawing.

Application filed April 13, 1929. Serial No. 354,984.

The invention relates to a method of decorating articles made of leather, silk, satin, or the like.

It is common knowledge that articles of the general type herein disclosed as examples, viz., ladies' shoes, pocketbooks, handbags, and similar appurtenances, will, after extensive or hard use, become worn and unsightly, with the result that they must be discarded, even though their actual utility is not yet exhausted. Naturally, this involves waste and expense.

An object of this invention is to make possible further use of articles made of leather, silk, satin, or the like, which outwardly are worn and of bad appearance.

By the practice of this invention, articles of the type described may be rehabilitated to produce novel, pleasing and attractive things, and extend their life and usefulness.

Another object of the invention is to produce, by the method disclosed, an article which is inexpensive and which will obviate the necessity of incurring large expense in replacements by the purchase of new ones.

In carrying out the method of decorating leather articles, the outer finished surface or grain leather is removed from the layers underneath, or at least to the extent that the worn and defaced integument will be removed and a proper surface for the subsequent operations provided. In the case of kid or patent leather, the grain surface when once started will easily peel off, while with heavier leather small portions of the grain surface at a time may be removed in order not to injure the underlying layers. This step in the method can be accomplished with any suitable instrument or machine, such as a knife, safety razor blade, or the like. It will be understood that the means for removing such outer layer in the first step of the method is not material, as various instrumentalities may be adopted.

When the grain surface has been removed there will remain an undecorated, absorbent, and slightly roughened surface to which is applied a suitable foundation and which I call a "leather skin." This "leather skin" consists of any suitable commercial paint

mixed with some suitable oil, to produce a mixture of proper consistency which will be readily absorbed by the skinned surface. The paint thus applied is the motif in the completed design, and may be suitably and variously colored in accordance with the scheme being worked out.

This foundation coat of paint is allowed to dry, preferably for at least a day, or at least until such time as will result in a thoroughly cured foundation.

The desired design having been decided upon, it is then painted, preferably by hand, on the foundation, with oil paints of high quality. The slightly roughened surface of the leather gives a splendid back-ground, both for adhesion and appearance, for the paints.

The article is then allowed to dry for a period, preferably of three days, but at least until it is completely set. It is quite important that this drying period be carefully observed in order to have the best results, as will be explained later.

The final step in the method is to finish the entire article with shellac, preferably a white shellac, and I have found that a plurality of coats, at least two, is desirable. A drying period of seven days at least is desirable and preferable, although this might be varied, after which the method is complete and the article finished.

If, before the oil painted design is sufficiently dry, shellac is applied, the tendency will be to make the various colors run together, and thus spoil the design effect. If the oil painted design is allowed to dry too long before the shellac is applied, there will be a tendency to crack, because the protective shellac coating does not then blend with the set but still flexible painted design. Therefore, the correct procedure of applying the method is desirable and must be observed.

The method of decorating is not limited to leather goods necessarily, but may be applied to silk and satin articles, such as shoes, handbags, pocketbooks, and the like. In the case of silk and satin articles, the foundation or base paint upon which the design motif is predicated, is made of suitable commercial

paint of high quality, thinned with gasoline to a proper consistency. When this has dried for a period of three days, the desired design is hand painted with oil paints, and after another three day drying period, the two coats of white shellac are applied. When this has dried, the operation is complete.

When once the design, according to this method, has been applied to an article, it can 10 again be shellacked from time to time to renew and preserve the brilliancy and lasting qualities of the design.

While the invention, as I have practiced it, is applied to old and worn articles of the 15 character described, it has found great popularity in its application to new articles before they have been used.

The finished product is an article of novel make-up which is not only very attractive 20 in appearance, but also wears surprisingly well. The design will not crack or chip off, nor will it be spoiled or lose its attractiveness when subjected to bad weather conditions. The finish is waterproof and the 25 colored design is adequately protected from moisture and dirt, which may be washed or brushed from the shellacked surface.

I claim:

1. The method of decorating articles of 30 the class described, which consists in imposing upon the article a foundation coat of paint to form the design motif, drying such foundation coat to the extent that it will not soften and mingle with other paints subsequently imposed thereon, thereafter painting on such foundation coat a decorative design of such form and color as to contrast with the foundation coat, subjecting the article to a second drying sufficient to set the 35 foundation and decorative design against softening and mingling with other coatings subsequently imposed thereon, and finally applying a colorless finishing and protecting coating of white shellac, and drying such shellac coating.

2. A method of decorating leather which 40 consists in removing the grained surfaces thereof to provide a liquid absorbing surface, applying to the ungrained surface a foundation coat of paint to form the design motif, drying such first coat to the extent that it will not soften and mingle with other paints subsequently imposed thereon, thereafter painting on such foundation coat a 45 decorative design of such form and color as to contrast with the foundation coat, subjecting the leather to a second drying sufficient to set the foundation and decorative design against softening and mingling with other coatings subsequently imposed thereon, and finally applying a finishing and protecting coating thereto and drying such finishing coating.

3. A method of decorating leather which 55 consists in removing the grained surfaces

thereof to provide a liquid absorbing surface, applying to the ungrained surface a foundation coat of paint to form the design motif, drying such first coat to the extent that it will not soften and mingle with other paints subsequently imposed thereon, thereafter painting on such foundation coat a decorative design of such form and color as to contrast with the foundation coat, subjecting the leather to a second drying sufficient to set the foundation and decorative design against softening and mingling with other coatings subsequently imposed thereon, and finally applying a transparent finishing and protecting coating thereto and drying such transparent finishing and protecting coating.

4. A method of decorating leather which 60 consists in removing the grained surface thereof to provide a liquid absorbing surface, applying to the ungrained surface a foundation coat of paint to form the design motif, drying such first coat to the extent that it will not soften and mingle with other paints subsequently imposed thereon, thereafter painting on such foundation coat a decorative design of such form and color as to contrast with the foundation coat, subjecting the leather to a second drying sufficient to set the foundation and decorative design 65 against softening and mingling with other coatings subsequently imposed thereon, and finally applying a finishing and protecting coating of white shellac and drying such shellac coating.

In testimony whereof I have hereunto set my hand.

DOROTHY FLEETWOOD.
